UNITED STATES PATENT OFFICE

169,129

TOY SIGNAL TOWER

Lawrence Cowen, New York, N. Y., assignor to
The Lionel Corporation, New York, N. Y., a
corporation of New York

Application February 23, 1952, Serial No. 18,645

Term of patent 14 years

(Cl. D34—15)

To all whom it may concern:

Be it known that I, Lawrence Cowen, a citizen of the United States of America, and a resident of the city of New York, county and State of New York, have invented a new, original, and ornamental Design for a Toy Signal Tower, of which the following is a specification, reference being had to the accompanying drawing, forming a part thereof.

In the drawing:

Figure 1 is a perspective view of the toy signal tower from the front showing my new design; and

Figure 2 is a perspective view of the same from the rear.

I claim:

The ornamental design for a toy signal tower, as shown.

LAWRENCE COWEN.
